(57) **CLAIM**

The ornamental design for a projector lamp, as shown and described.

DESCRIPTION

FIG. 1 is a perspective view of a projector lamp according to an embodiment of my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the projector lamp shown in FIGS. 1-8;

FIG. 10 is a perspective view of a projector lamp according to another embodiment of my design;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is an exploded perspective view of the projector lamp shown in FIGS. 10-17.

The broken lines in the drawings depict portions of the projector lamp that form no part of the claimed design.
